MACHINE FOR CUTTING SHEETS

Gennero De Croce, Kenmore, N. Y., assignor to
 Westinghouse Electric & Manufacturing Company, East Pittsburgh, Pa., a corporation of Pennsylvania

Application August 2, 1940, Serial No. 349,788

1 Claim. (Cl. 164—73)

My invention relates to control systems for sheet cutting machines, and more particularly to systems of control for cutting glass, or other plastic material.

Heretofore in the cutting of glass, plastic glass is fed vertically through sizing rolls vertically into a cutting machine. This machine has a frame and a limiting bar or stop. When the limiting bar is moved to its limit, the glass feeding is stopped and a scoring tool is manually moved over the face of the glass to score it. The attendant bumps the sheet to break it on the score line and then removes it manually to a platform or conveyor. The cycle is then repeated.

One object of my invention is to make all the operations automatic to eliminate the time, labor, and cost of producing glass plates or sheet, or plates or sheets of similar material, as stiff rubber, plyboard, paper, or the various plastics.

Another object of my invention is to increase the efficiency of producing glass sheets.

Other objects of my invention will become more apparent from a study of the following specification and the accompanying drawing, in which:

Figure 1 is a front view of a glass cutting machine, shown somewhat schematically;

Fig. 2 is a side view of the showing in Fig. 1;

Fig. 3 is a diagrammatic showing of the electric control for the glass cutter motor; and

Fig. 4 is a diagrammatic showing of the electric control for the glass remover motor.

The best understanding of my invention may be had from a study of a typical operating sequence or cycle of operation. Assuming the various buses, indicated by the plus and minus signs are energized, then an energizing circuit is established through conductor 1 (Fig. 3) through glass-movement limit switch 2, actuating coil 3 of control relay 5 to the negatively energized conductor 4.

Operation of control relay 5 causes the closing of contact members 9 and opening of contact members 29 and 38. Opening of contact members 29 and 38 prevents energization of the control relay 37 and the forward directional contactor 31 so that no false operation may be obtained. Closing of contact members 9 establishes a circuit from conductor 7, through conductor 8, contact members 9, limit switch 10, actuating coil 11 of reverse directional contactor 12, to conductor 13.

Operation of reverse directional contactor 12 closes the contact members 15 and 17 to ener-

gize the cutter operating motor M. The circuit for the motor may be traced from conductor 14 through contact members 15, armature 16, contact members 17, field winding 18 to the negative line.

The motor M, coupled to shaft 19 (see Figs. 1 and 2), thus drives the threaded member 20 through reduction gear 21. The nut 22 mounted on the member 20 and restrained from rotation by the cutter guides 23 thus moves the cutter 24, coupled to the nut 22, to the start position, which, as shown in Fig. 1, is the left-hand position.

When the cutter or nut is in the start position, it actuates the limit switch 10. This operation thus opens the circuit for coil 11, and the cutter is thus stopped in the start position.

The glass rolling and sizing machine (not shown) now moves a sheet of glass into the cage 25, and as it moves up it engages vertically slideable middle cross-member 26 which in turn moves up and operates limit switch 2 to open it. Opening of limit switch 2 deenergizes control relay 5 and in consequence contact members 29 and 38 are closed. Opening of limit switch 2 also stops feeding of the glass to frame 25 by suitable means old in the art.

Closure of contact member 38 does not yet close a circuit at this stage, but the closure of contact member 29 establishes a circuit from conductor 27, through contact members 28 and 29, actuating coil 30 of forward directional contactor 31 to conductor 13. Operation of forward directional contactor 31 now establishes a circuit for motor M, which circuit may be traced from conductor 14 through contact members 32, armature 16, contact members 33 and field winding 18 to the negative line.

The motor thus operates in the forward direction, thus operating the cutter transverse of the sheet of glass, that is, to the right in Fig. 1, and scores the glass sheet. The cutter may either cut the glass all the way through, or preferably merely score it. When the cutter arrives at the extreme right, it actuates the bumper bar 34 by means of a cam, or bell crank lever, or other means (not shown) coacting with nut 22. The bumper bar strikes the glass and breaks it on the line of the score, so that the sheet is ready for removal. The nut 22 also actuates the limit switches 35 and 41 to close them.

Closure of limit switch 35 energizes coil 36 of control relay 37, and this relay holds itself in through contact members 38 and 39. By the

opening of contact members 38, they stop the forward operation of the motor M. Relay 37 also closes contact members 40 and thus starts the motor to return the cutter, and when the cutter is returned limit switch 10 opens to stop the cutter in the start position.

It will be noted that no cycle of operation can now be started until the glass is removed, since limit switch 2 is still held open by member 26. However, because of the closure of limit switch 41, already mentioned, a circuit is established for control relay 44, and this relay holds itself in through limit switch 42 and contact members 43.

Operation of control relay 44 also closes contact members 45, thus causing operation of the forward directional contactor 46, and also causes opening of the contact members 47 to prevent operation of control relay 48 and thus the operation of the reverse directional contactor 49.

Operation of the forward directional contactor 46 establishes a circuit for glass removing motor M', which circuit may be traced from line 50 through contact members 51, armature 52, contact members 53, field 54 to the negative line. The motor M' thus, through pinion 56 and sector 57, operates frame 55 clockwise to lay the glass sheet on the conveyor belt or platform 58.

As the glass is removed, limit switches 2 and 59 are closed. Closure of limit switch 2 merely again starts movement of glass into cage 25 and also effects shunting of contact members 40 through operation of relay 5; so as to make the return movement of the cutter for the time being independent of control relay 37. In other words, if the cutter is not yet in the start position, it will continue to move to that position regardless of control relay 37 until limit switch 10 is opened.

Closure of limit switch 59 does nothing until limit switch 42 is opened. Limit switch 42, however, opens when the glass is on the conveyor, and since limit switch 41 is already open, control relay 44 is deenergized, closing contact members 47 to thus actuate relay 48 to close contact members 60. Closure of contact members 60 actuates reverse directional contactor 49.

Operation of reverse directional contactor es-

tabishes a circuit from the positive line 60 through contact members 62, armature 52, contact members 63 and field 54 to the negative line. The motor M' thus operates to reposition frame 55 to receive another sheet of glass. When the frame 55 is again in vertical position, limit switch 59 is opened and motor M' is thus stopped. The cycle may now repeat itself as soon as bar 26 again opens limit switch.

From the foregoing, it is apparent that I have provided a very efficient control for a glass cutting machine or a machine cutting similar plastic material. The production is thus very materially increased, and time, labor and money are saved. Further, voltage failure sets the circuits so that the cutter is returned to the start position upon return of voltage.

I am, of course, aware that others, particularly after having had the benefit of my teachings may devise other circuit diagrams for accomplishing the same or similar novel results, I, therefore, do not wish to be limited to the particular system of control shown and described, but wish to be limited only by the scope of the claim hereto appended.

I claim as my invention:

In a machine for producing sheets of fairly rigid material, in combination, a cage, means for moving sheet material into the cage, an electric motor, a cutter connected to be operated by the motor, means responsive to the movement of a given length of sheet material into the cage to stop the means for moving the sheet material into the cage and for initiating the operation of the motor operating the cutter to thus cut a given length of sheet material, a second electric motor, sheet removing means connected to be operated by the second motor, and means, responsive to the completion of the cutting of the sheet, for causing the operation of the said second motor, and means, responsive to the completion of the removal of the sheet from the cage, for starting the means for moving the sheet material into the cage.

GENNERO DE CROCE.
